UNITED STATES PATENT OFFICE.

LEONARD E. ASKE, OF DULUTH, MINNESOTA.

MANIFOLD HEATER.

Application filed March 9, 1925. Serial No. 14,152.

My invention relates to manifold heaters and has for its object the provision of an improved structure for trapping heat from the exhaust manifold and applying it to the intake manifold of an internal explosion or hydrocarbon engine for the purpose of heating and vaporizing the charge of fuel before said fuel is delivered to the piston cylinder. With this and other objects in view, my invention consists of the structures, combinations and arrangements of parts hereinafter described and claimed.

In the drawings, Fig. 1, is a side view of my said invention, omitting the hereinafter described engine block. Fig. 2, is an enlarged vertical transverse view on the line A—B of Fig. 1, a fragment of said engine block being included. Fig. 3, is a front view of a partly finished cover forming part of said invention. Fig. 4, is a top end view of said cover in completed form. Fig. 5, is a side elevation of a filling pad or rear panel forming part of my said invention, and Fig. 6 is a top view of said cover, filling pad and a portion of said engine block; the herein-after described manifolds being omitted to more clearly disclose the position of the cover and filler pad with respect to said engine block.

In the drawings, 1 is an engine block, provided with exhaust ports extending through bosses 1^a 1^b, which ports are adapted to register with and discharge into corresponding opposite ports in depending lugs 2^a and 2^b forming part of an exhaust manifold 2. Positioned below said exhaust manifold is an intake manifold 3, upon which is formed an upwardly directed central dome 3^a adapted to extend into the space between said lugs 2^a and 2^b. A copper rod 4 preferably extends into said dome through the top thereof.

Overlapping a portion of the outer side of said intake manifold intermediate of its ends and also overlapping a portion of the outer side of said exhaust manifold intermediate of its ends, is a close shield or cover 5 which is provided with wings 5^a and 5^b, which wings are adapted to extend between the intake and exhaust manifolds to the side wall 50 of said engine block, so as to closely overlap said bosses 1^a and 1^b and said lugs 2^a and 2^b. The top and bottom edges of said wings are cut away or formed so as to conform to the curvature of the lower side of said exhaust manifold and the upper side of said intake manifold, respectively. Inserted into the

space between the sides of said intake and exhaust manifolds and the side of said engine block and extending from said boss 1^a to said boss 1^b is a rear panel or space filler 5^c of any suitable material, as asbestos, the construction being such that the space between said lugs 2^a and 2^b and between said panel and the central portion of said cover into which space said dome extends, is substantially boxed in by said exhaust and intake manifolds and by said cover, wings and rear panel, thus forming a heating chamber around said dome for trapping the heat radiated in said chamber by said exhaust manifold.

A lip 6, is preferably formed on the inner side of said intake manifold to support said rear panel. Said cover preferably has a ventilating port formed therein adapted to be covered or uncovered by a damper 7 for regulating the temperature of said chamber. Said cover preferably has hoods 8 and 9 formed thereon for receiving underlying bosses formed on said exhaust manifold, so that said cover may lie closely against the sides of said manifolds respectively.

I am aware that it is not broadly new to provide means for the purpose of absorbing heat radiated from an exhaust manifold and transmitting it to an intake manifold, but I am not aware of any provision for preventing the escape of such heat through passages or spaces between the manifolds and the engine block, or over or under said lugs.

It is obvious that my invention may be modified in various particulars within the scope of certain of my claims.

What I claim is:

1. In a manifold heater, the combination with an engine block, an exhaust manifold and an intake manifold, said manifolds being spaced from said block for a portion of their lengths intermediate of their ends, of a cover adapted to overlap a portion of the outer side walls of said manifolds, said cover being provided with end wings adapted to extend between said manifolds to the opposing side wall of said block, the upper and lower edges of said wings being adapted to conform closely to the contour of the lower side of said exhaust manifold and to the upper side of said intake manifold respectively, and a back panel adapted to fill the space between said block and the opposing side walls of said manifolds.

2. The combination with an engine block,

- an exhaust manifold and an intake manifold, of a cover adapted to overlap a portion of the outer side walls of said manifolds, said exhaust manifold having two lugs
5 formed thereon intermediate of its ends, said lugs extending to said block, said manifolds being spaced from said block for that portion of their lengths extending between said lugs, said cover being provided with
10 end wings adapted to extend between said manifolds to the wall of said block, said cover and wings being adapted to span said lugs, the upper and lower edges of said wings being adapted to conform respectively
15 to the lower face of said exhaust manifold and to the upper face of said intake manifold, and a rear panel space filler for filling the space between said block and the side walls of said manifolds extending between
20 said lugs.
3. In a manifold heater, the combination with an engine block of exhaust and intake manifolds, of a cover comprising a body portion adapted to overlap a portion of the outer side walls of both of said manifolds, and reduced wing portions extending at an angle from the opposite ends of said body portion, said end wings being adapted to ex-
- 25

tend between said manifolds to the face of said engine block.

4. In a manifold heater, the combination with an exhaust manifold and an intake manifold, of a cover adapted to overlap a portion of the outer side walls of both of said manifolds, said cover being provided with wings adapted to extend at an angle 30 between said manifolds, a back panel adapted to overlap a portion of the rearward side walls of both of said manifolds.

5. In a manifold heater, the combination with an exhaust manifold having depending lugs formed thereon containing ports, of an intake manifold having a vaporizing dome formed thereon extending between said lugs, a cover adapted to overlap a portion of the outer side walls of both of said manifolds, said cover being provided with wings adapted to extend at an angle between said manifolds, and a back panel adapted to overlap a portion of the rearward side walls of both 45 of said manifolds, said panel being positioned between said wings.

In testimony whereof, I hereunto affix my signature.

LEONARD E. ASKE.
